UNITED STATES PATENT OFFICE

CHARLES RUSSELL LANG, OF CATHCART, GLASGOW, SCOTLAND, ASSIGNOR TO G. & J. WEIR, LIMITED, OF GLASGOW, SCOTLAND

STEAM-POWER PLANT WITH CLOSED FEED SYSTEM

Application filed February 11, 1928, Serial No. 253,778, and in Great Britain February 26, 1927.

This invention relates to closed feed systems for steam power plants including a boiler, a boiler-feed-pump, a steam engine (which may be a turbine), a main condenser, 5 a water-extraction pump which deals with the feed water obtained by condensation of the steam in the condenser, and discharges this feed water under a pressure above atmosphere into the main feed conduit, whence 10 it passes to the boiler-feed-pump, and including also a reserve feed tank.

In closed feed systems it is desirable, for reasons well known, to avoid the inflow (into the feed system) of feed water from a tank 15 open to the atmosphere, except in just sufficient quantity as is required to make up losses.

As the water level in the boiler varies within certain limits, there necessarily results variation in the quantity of water in the rest of 20 the system, and it is necessary to provide for this variation. Withdrawal from, and discharge back into, an atmospheric tank is 25 objectionable as aforesaid.

In certain steam installations, for example, in high-power steam ships, there is often no room available for a well or tank of any considerable capacity below the condenser.

A proposal previous to the present one, and 30 applicable to a steam power plant which includes a boiler, a boiler-feed-pump, a steam engine and a main condenser, involves the employment of a de-aerating chamber which is maintained under the same pressure as that 35 in the main condenser by being connected thereto and the employment of a hotwell at the bottom of this chamber, this hotwell (which might be in an elevated position) serving primarily as a balancing chamber to 40 equalize the differences between the output from the condenser and the demands of the boiler: in this arrangement, make-up feed-water is sprayed into the de-aerating chamber and is supplied from a reserve feed tank 45 through a valve controlled by a float in the hotwell.

Now, in a steam power plant according to the present invention, no separate de-aerating chamber is provided; and make-up feed-water is supplied to the main condenser. A

steam power plant according to the present invention includes an elevated feed reservoir maintained under the same pressure as existent in the condenser (e. g. by means of an equilibrium pipe which connects the two), a 55 pipe connecting this reservoir—below the water level therein—with the suction of the water-extraction pump, a float in the reservoir, a valve in the pipe through which water is admitted to the condenser from the reserve 60 feed tank, and mechanism whereby said valve is controlled by the said float so as to be closed with a high position of the float and opened by a fall of the float.

How the invention can be carried into effect will now be described by reference to the accompanying drawing which is diagrammatic. The invention will be defined in the annexed claim.

x is the main turbine: *a* is the main condenser: *c* is a suction head pump which withdraws the feed water from the condenser through the pipe *h* and delivers it into the pipe *m* which leads to the water-extraction pump *d* and has an upwardly-extending 70 branch *n* which leads to the elevated feed reservoir *r*. An equilibrium pipe *v* connects together the steam spaces in the reservoir *r* and the steam condenser, so as to maintain the same pressure in the former as in the latter. 75 Except for flow up or down the pipe *n* to meet irregularities, the pump *d* delivers all the feed water into the main feed conduit *s*. *e* is the boiler-feed-pump and *w* the boiler. *u* is the reserve feed tank. 80

The reservoir *r* contains a float *g* which by a suitable mechanism controls a valve *f* placed on the pipe *t* which connects the reserve feed tank *u* with the condenser. 85

When, due to a reduced delivery of water 90 into the boiler, the pressure rises in the main feed conduit, and hence in the pipe *m*, there is a flow of water into the reservoir *r*, and, under the opposite conditions, there is a flow 95 from the reservoir *r* into the pipe *m*. A certain pre-determined range of water level in the reservoir is provided for. When the water level falls below the pre-determined low level, the valve *f* is opened and a flow of 100

water takes place from the reserve feed tank into the condenser.

By means of the present invention, therefore, it will be seen that fluctuations in the working of the system are provided for, and 5 water admitted to the system only when necessary, and then automatically.

Having thus described my invention, what I claim as new and desire to secure by Letters Patent is:—

- 10 A steam power plant having the feed system arranged as a closed-feed system and including a boiler, a steam engine (which may be a turbine), a main condenser, a main feed conduit, a water-extraction pump which 15 deals with the feed water obtained by condensation of the steam in the said condenser and discharges this feed water under a pressure above atmosphere into the said main feed conduit, a boiler feed pump which discharges the feed water from the said main feed conduit into the said boiler, a reserve feed tank open to the atmosphere, an elevated feed reservoir, means for maintaining the 20 said elevated feed reservoir under the same pressure as existent in the said condenser, a pipe connecting the said reservoir—below the water lever therein—with the suction of the said water-extraction pump, this pipe serving 25 as means for to-and-fro movement of feed water between the said reservoir and the suction of the said pump, a float in the said reservoir, a pipe connecting the said condenser with the said reserve feed tank, a valve 30 on this last-mentioned pipe, and mechanism 35 whereby the said valve is controlled by the said float so as to be closed with a high position of the float and opened by a fall of the float.

40 I hereby sign my name to this specification.
CHARLES RUSSELL LANG.
